UNITED STATES PATENT OFFICE.

NEEDHAM W. HURST, OF MACON, GEORGIA.

TOBACCO RACK.

Application filed March 29, 1928. Serial No. 265,731.

This invention relates to a rack for holding leaf tobacco while being cured, one of the objects being to provide a simple, compact and efficient device by which stripped leaves can be securely gripped and supported at a considerable saving of time and labor as compared with the old methods of mounting the leaves on strings and sticks.

With the foregoing and other objects in view which will appear as the description proceeds the invention resides in the combination and arrangement of parts and in the details of construction hereinafter described and claimed it being understood that changes in the precise embodiment of the invention herein disclosed may be made within the scope of what is claimed without departing from the spirit of the invention.

In the accompanying drawings the preferred form of the invention has been shown.

In said drawings,

Figure 1 is a perspective view of the rack supported in position for receiving the tobacco leaves to be cured, some of the leaves being shown in engagement therewith prior to being gripped.

Figure 2 is a top plan view of the rack, the gripping bars being shown open.

Figure 3 is a similar view showing the gripping bars closed.

Figure 4 is a section on line 4—4, Figure 3.

Referring to the figures by characters of reference 1 designates a pair of parallel connecting bars formed preferably of wood. Attached to these bars near one end is an end gripping bar 2 the inner side of which is formed with a gripping surface 3 following an ogee curve from top to bottom as shown particularly in Figures 1 and 4. The connecting bars 1 are provided with additional gripping bars 4 extending transversely thereof but shorter than the bar 2, all of these gripping bars being parallel and all of them being provided at corresponding sides with gripping surfaces shaped to form ogee curves as shown.

Another pair of connecting bars 5 is located between the bars 1, these bars 5 slidably engaging the inner sides of the bars 1.

An end gripping bar or slat 6 is fastened to the bars 5 near one end and the inner longitudinal edge of the gripping bar or slat 5 is shaped to provide an ogee curve as shown at 7 which overhangs and is adapted to co-

operate with the corresponding gripping bar or slat 4 adjacent thereto. Additional shorter gripping bars or slats 8 are attached to the connecting bars 5 and are also formed with overhanging gripping edges forming ogee curves and cooperating with the gripping edges of the adjacent bars 4 and 3.

Secured to one of the bars 8 is a block 9 having a longitudinal tongue 10 extending from one side portion thereof. Another block 11 is secured to one of the bars or slats 4 and has a longitudinal tongue 12 extending from one side portion thereof. The two tongues 10 and 12 are adapted to extend side by side and a lever 13 is pivotally connected at 14 and 15 to the respective tongues. Loose connections are provided at the pivots 14 and 15 so that the lever will have a certain amount of play to compensate for the variations between the swinging movement of the lever and the right line movement of the tongues. Furthermore the lever is free to swing slightly toward and from the gripping bars or slats.

The bars 1 and 5 at one side of the rack are provided with obliquely disposed grooves 16 adapted to aline when the gripping bars are moved apart as shown in Figure 2. While the grooves 16 are thus alined they are positioned to receive the lever 13 as shown in said Figure 2. Thus the bars will be held spaced apart. Another pair of obliquely disposed grooves 17 is provided in these bars 1 and 5 but are only adapted to aline when the gripping bars or slats are pressed toward each other. At that time the grooves 17 are located where the lever 13 can be seated therein as shown in Figure 3. Thus the bars or slats 4 and 8 will be held against movement away from each other. For the purpose of securing the lever 13 in the grooves 17 a button 18 may be pivotally mounted on the bar 5 so as to lap a flange 19 formed on the lever. This arrangement of the parts has been shown in Figure 3.

In using this rack the same is placed on end with the bars 5 resting on the ground or floor and the rack supported in an inclined position with the gripping bars or slats spaced apart, as shown in Figure 3. After the tobacco leaves have been stripped from the stalks they are laid with their stems between the gripping bars or slats as shown in Figure 1. After the spaces between these bars or slats have been filled, the lever 13, which has been seated in the grooves 16, is

shifted out of said grooves and then pulled to its other extreme position so as to become seated in the grooves 17.

The operation heretofore described will 5 result in the tongues 10 and 12 being drawn toward each other and the gripping bars or slats will come against and tightly engage the stems therebetween. Lever 13 can then be secured by means of the button 18. Supporting ropes can then be attached to the projecting ends of the bars 1 and 5 and the rack, with the leaves suspended therefrom as shown in Figure 4, can be elevated so that the projecting ends of the bars or 15 slats 2 and 6 will come against the rafters of the curing shed and which have been indicated by broken lines at R in Figure 2. When it is desired to remove the leaves it is merely necessary to lower the rack again 20 place it in an inclined position and shift the gripping bars or slats from each other so as to release the leaves whereupon they can be lifted from the rack and said rack can then be refilled.

25 Importance is attached to the fact that this rack is formed almost entirely of wood and can be made cheaply. It is durable and easily handled.

What is claimed is:

30 1. A tobacco rack including parallel gripping bars arranged in pairs, the bars of each pair having gripping edges adapted to overlap, and means for simultaneously shifting the bars of the respective pairs to move them into or away from gripping positions.

40 2. A tobacco rack including parallel connecting bars arranged in pairs, transverse gripping bars arranged in pairs, one bar of each pair being attached to one pair of connecting bars and the other bar of each pair being attached to the other pair of connecting bars, said gripping bars having gripping edges adapted to overlap, and

means for simultaneously shifting the gripping bars toward or from each other. 45

3. A tobacco rack including parallel connecting bars arranged in pairs, parallel gripping bars arranged in pairs, one gripping bar of each pair being attached to one pair of connecting bars and the other gripping bar of each pair being attached to the other pair of connecting bars, said gripping bars having gripping edges adapted to overlap, an actuating lever, connections 50 between said lever and the respective bars of the pairs, and means carried by one of the connecting bars of each pair for engagement by the lever to hold said bars against relative movement when the lever is in either 55 of two extreme positions.

4. A tobacco rack including parallel connecting bars arranged in pairs, parallel transversely extending gripping bars arranged in pairs, one bar of each bar being fastened to one pair of connecting bars and the other gripping bar of each pair being connected to the other pair of connecting bars, all of the gripping bars having gripping edges adapted to overlap, a block 60 movable with one gripping bar of each pair, another block movable with the other gripping bar of each pair, an actuating lever pivotally connected to the two blocks, there being grooves within one of the connecting bars of each pair, certain of said grooves being arranged to receive the lever when the gripping bars are moved apart maximum distances and the other grooves being adapted to receive the lever when the gripping bars are moved toward each other to 65 gripping positions, and means on one of the connecting bars for holding the lever in the last named grooves. 70

In testimony that I claim the foregoing 85 as my own, I have hereto affixed my signature.

NEEDHAM W. HURST.
